DESIGN FOR A PIANO

Louis Bromberg, Rockaway Park, N. Y.

Application May 29, 1943, Serial No. 110,325

Term of patent 14 years

To all whom it may concern:

Be it known that I, Louis Bromberg, a citizen of the United States of America, and resident of Rockaway Park, county of Queens, and State of New York, have invented a new, original, and ornamental Design for a Piano, of which the following is a specification, reference being had to the accompanying drawing, forming a part thereof.

Fig. 1 is a perspective view of a piano, showing my new design; and

Fig. 2 is a side elevational view thereof, on an enlarged scale.

I claim:

The ornamental design for a piano, substantially as shown.

LOUIS BROMBERG.
